C. F. BUSCHKE

INTERNAL COMBUSTION ENGINE

Filed June 13, 1919

Inventor:
Charles F. Buschke,
by Botham Botham Hudnall Lecher
Attorneys.

UNITED STATES PATENT OFFICE.

CHARLES F. BUSCHKE, OF MILWAUKEE, WISCONSIN.

INTERNAL-COMBUSTION ENGINE.

Application filed June 13, 1919. Serial No. 303,927.

To all whom it may concern:

Be it known that I, CHARLES F. BUSCHKE, a citizen of the United States, residing at Milwaukee, in the county of Milwaukee and State of Wisconsin, have invented certain new and useful Improvements in Internal-Combustion Engines, of which the following is a specification, reference being had to the accompanying drawing, forming a part thereof.

This invention relates more particularly to fuel injecting and regulating devices for internal combustion engines.

The main objects of the invention are to adapt fuel injecting and regulating apparatus to engines of different types operated under different conditions and with fuel of different grades; to thoroughly atomize or vaporize oil of lower grades as it is injected into an engine cylinder; to provide for the injection of oil with or without the admixture of air before it enters the cylinder; and generally to improve the construction and operation of apparatus of this class.

It consists in the construction, arrangement and combination of parts as herein-after particularly described and pointed out in the claims.

In the accompanying drawing like characters designate the same parts in both figures.

Figure 1 is a vertical axial section of a single upright cylinder, two-cycle, internal combustion engine embodying the invention; and Fig. 2 is an enlarged sectional detail view of the spray nozzle and fuel valve.

While the fuel injecting and regulating apparatus to which the present invention particularly relates is applicable to internal combustion engines of different types, it is shown in the drawing and will be described in detail, as applied to a two-cycle engine.

Referring to Fig. 1 of the drawing, the engine comprises a cylinder 1, provided with an exhaust port 2 and a compressed air inlet port 3, a closed crank case and base 4, on which the cylinder is mounted and with which it communicates through its open lower end, a trunk piston 5, and a crank shaft 6, having bearings in the case and base 4 and directly connected by a rod 7 with the piston. A valve case 10, mounted on the cylinder head, is provided at its lower end with a spray nozzle 11, detachably connected with the case by screwthreads.

The nozzle 11 is formed, as shown in Fig.

2, with three coaxial beveled valve seats 13, 14 and 15 of diminishing diameter towards its lower end, and is fitted and inserted as shown in Fig. 1, in an opening in the cylinder head. A number of small divergent spray passages 17, lead from the seat 15 through the inner end of the nozzle into the engine cylinder.

The valve case 10 is formed or provided at its upper end with an enlarged cylinder extension 19, which is provided at its upper end with a screw cap 20.

A fuel valve 22, formed with three coaxial beveled working faces, fitted accurately to the seats in the nozzle 11, as shown in Fig. 2, is provided with a reduced shank which is threaded in a socket in the lower end of a stem 23. The stem 23 is fitted and guided in the valve case 10 above the nozzle 11, and is provided with a piston 24, which is fitted and works in the cylinder extension 19, the upper reduced end of the stem passing freely through a hole in the cap 20.

A passage 25, extending axially through the stem 23 into the body of the valve 22, communicates with the lower or inner end of the cylinder extension 19 through lateral ports 26, and with an internal annular recess 27 in the valve case, through lateral ports 28. At its lower end the passage 25 communicates with a clearance space between the nozzle 11 and valve 22, and between the valve seats 13 and 14 and the corresponding valve faces, through divergent passages 30. This clearance space is preferably enlarged by flattening the sides of the valve adjacent the outer ends of the passages 30 between the valve faces working with the seats 13 and 14, as shown in Fig. 2.

Between the lateral ports 26 and 28 the valve stem is provided in the passage 25 with an outwardly closing check valve 32 and also with an air controlling and regulating valve 33, the stem of which, extending upwardly or outwardly through the stem 23, is threaded therein and provided at its upper or outer end with a head 34. The head 34 is enclosed and protected by a removable cap 36, threaded on the top of the cap 20, to prevent accidental or unauthorized displacement of or interference with the valve 33.

A spring 38, interposed between the cap 20 and piston 24, tends to close the valve 110

22 and to hold said piston at the lower or inner limit of its movement.

The valve stem 23 is provided with packing rings above and below or on opposite sides of the ports 28, to prevent oil from leaking from the recess 27 upwardly or downwardly around the stem, and air from leaking from the lower end of the cylinder extension 19 downwardly around the stem.

10 The cylinder extension 19 is provided with a gage 40, for indicating any leakage of oil into the space above the piston 24.

The fuel valve 22 may be opened at the proper times by the pressure of the oil supplied thereto, or by air compressed by the engine piston, or when available, by compressed air obtained from an independent source, according to varying conditions.

As shown by the drawing, oil is supplied 20 to the engine under control of the valve 22 from a tank or reservoir 42 by a two-stage pump comprising two parallel cylinders 43 and 44, and plungers 45 and 46. The low pressure cylinder 44 is connected 25 with the reservoir 42 by a pipe 47, provided with a check valve 48 opening towards the pump. The high pressure cylinder 43 is connected with the annular recess or cavity in the valve case 10 by a pipe 50, provided 30 with a check valve 51 opening away from the pump, and by a branch pipe 52 provided with a cut-off valve 53. The pump cylinders are connected with each other by a passage 55, provided with a check valve 35 56 opening towards the high pressure cylinder. The high pressure cylinder is connected with the pipe 47 or with the reservoir 42 by a by-pass pipe 58, which is provided with a relief valve 59 opening towards 40 the reservoir and closed by a spring, the tension of which is adjusted by a screw 60. The pump plungers 45 and 46 are connected with a rocker arm or lever 62 on opposite sides of its fulcrum and the lever 62 is connected 45 by a rod 63 with the strap of an eccentric 64 on the crank shaft 6. The pipe 50 is connected with the lower end of the cylinder extension 19 by a pipe 66 and a branch pipe provided with a cut-off valve 50 67.

When the fuel valve 22 is to be operated by the pressure of the oil supplied to the engine, the valves 53 and 67 are both opened, and with each working stroke of 55 the high pressure plunger 45, oil is forced through the pipes 50 and 66 and the branch pipe 52 into the recess or cavity 27 of the valve case, and into the lower end of the cylinder extension 19. The pressure exerted by the oil on the lower end of the piston 24, lifts and opens the valve 22 and simultaneously therewith a charge of oil is forced through the ports 28, passage 25 and branch passages 30 into the space between the valve seats 13 and 14, from which

it is forced through the spray passages 17 into the engine cylinder. The oil flowing in a circuitous course from passage 25 through the branch passages 30 into the clearance space around the valve between 70 the seats 13 and 14, thence between the seats 14 and 15 and opposing faces of the valve and finally through the divergent spray passages 17 into the cylinder, is finely subdivided and heated by contact with the hot 75 nozzle 11 and valve 22 which become highly heated by the operation of the engine, and issues from the passages 17 in a gaseous or vaporous condition, best adapted to operate the engine.

The extent of opening of the valve 22, and hence the volume of the fuel charge injected into the engine and cylinder, are regulated by the adjustment of the screw 60, which determines the amount of oil 80 forced by the pump into the cylinder extension 10 under the piston 24 with each working stroke of the high pressure plunger 45. The pump plungers working alternately, the downward stroke of the low 85 pressure plunger 46 draws oil from the reservoir 42 through the pipe 47 and check valve 48, into the cylinder 44. The high pressure plunger 45 being withdrawn downward as the low pressure plunger 46 makes 90 its upward working stroke, the oil in the cylinder 44 is forced through the passage 55 past the check valve 56, into the cylinder 43. With the upward working stroke 95 of the plunger 45, oil is forced through the check valve 51, pipe 50 and its branch connections, into the valve case 10, keeping the oil spaces and passages therein and in the fuel valve filled, and into the lower end of the cylinder extension 19 below the piston 100 24. Any excess of oil above that required for the operation of the engine and of the fuel valve 22 according to the adjustment of the screw 60 which determines the pressure 105 of the spring against the check valve 59, is forced back through the by-pass pipe 58 into the reservoir 42. The fuel valve 22 may be operated, under conditions making it desirable to do so, by air pressure supplied by the engine itself, or from an independent source. When the engine is to supply compressed air for the operation of the fuel valve and when desired, for admixture with the oil before it is injected into the engine cylinder, the lower end of the cylinder extension 19 below the piston 24, is connected, as by the pipe 66, a branch pipe 69 provided with a cut-out valve 70, and distributing valve mechanism, with the closed end of the engine cylinder 1.

The distributing valve mechanism may consist as shown, of a piston valve 72 working in a case 73, which is fitted and secured in an opening into the engine cylinder, and with which the pipe 69 is connected. At its 110

inner end the valve 72 is connected by a stem with a valve 74, which is seated in and normally closes a passage in the valve case leading from the engine cylinder into the 5 chamber of the valve 72. At its outer end the valve 72 is provided with a stem 75, which projects outwardly through the cap of the valve case. The valve 72 is formed with an angular or curved port 77, 10 communicating at one end with the passage leading from the engine cylinder and adapted to register at the other end with a port 78 in the adjacent side of the valve case. The valve 72 is also formed with a through 15 port 79, adapted to register at the ends simultaneously with a port 80 and an exhaust port 81 in the valve case 73. The ports 78 and 80 have a common connection with the pipe 69, and the exhaust port 81 20 is connected by a pipe 83 with the exhaust pipe 84 of the engine. The pipe 83 is provided with a check valve 86, which closes towards the valve 72.

A spring 88, acting on the valve stem 25 75, tends to hold the valve 74 closed, and the valve 72 with its port 79, in register with the ports 80 and 81. The valve 74 is opened and the valve 72 simultaneously shifted to bring the port 77 into register 30 with the port 78 and the port 79 out of register with the ports 80 and 81 near the end of the compression strokes of the engine piston 5, by a bell crank lever 90 engaging the outer end of the stem 75 and connected 35 by a rod 91 with a cam roller or follower 92, engaging a cam 93 on the crank shaft 6. The lever 90 has an adjustable eccentric fulcrum bearing 95 in a bracket attached to the valve case 73.

40 The eccentric bearing 95 is provided with an arm 96, which may be connected by a rod 97 with a governor (not shown) for automatic regulation of the speed of the engine.

45 When the fuel valve 22 is to be operated with air compressed by the engine piston 5, the valve 67 is closed and the valve 70 opened. Towards the end of the compression stroke of the piston 5 the valve 74 50 is opened by the cam 93 and the piston valve 72 is shifted to carry the port 77 into register with the port 78 and the port 79 out of register with the ports 80 and 81. Compressed air thus admitted from the engine cylinder 1 through the pipes 69 and 66 into the cylinder extension 19, acts on the lower end of the piston 24 to open the fuel valve 22 and permit the injection of a charge of fuel into the engine cylinder. 55

60 As the fuel valve 22 is opened, the pump plunger 45 forces oil through the pipe 50, branch pipe 52 and passage 25 into the space between the valve and nozzle 11, and thence through the spray passages 17 into 65 the engine cylinder. The fuel thus injected

into the engine cylinder in a fine spray or gaseous form and mingled with the air compressed by the piston 5, is ignited by contact with the hot cylinder head and piston, or other well known means (not 70 shown). The resulting explosion of the mixture of gas or oil vapor and air drives the piston 5 downward or towards the crank shaft. During the downward or working stroke of the piston 5 the valves 72 and 74, 75 released by the cam 93, are shifted outward by the spring 88, closing the valve 74 and carrying the port 77 out of register with the port 78 and the port 79 into register with the ports 80 and 81. Compressed air 80 is thus released from the cylinder extension 19 through the pipes 66 and 69, ports 80, 79 and 81 and pipe 83, and is discharged into the engine exhaust pipe 84. The fuel valve 22 is thereupon closed by the spring 38. 85

Another charge of oil is forced by the pump plunger 46 from the cylinder 44 into the upper end of the cylinder 43, to be forced by the next upward movement of the high pressure plunger 45 through the 90 pipes 50 and 52 and the passage 25, into the clearance space between the nozzle 11 and the valve 22 and between the valve seats 13 and 14.

The traverse of the distributing valve 95 72 and of the valve 74 is varied to regulate the opening of the fuel valve 22 and the supply of fuel to the engine cylinder by the adjustment of the eccentric bearing 95 of the lever 90. 100

When an independent source of compressed air is available, it may be utilized for operating the fuel valve 22, and, when desired, for admixture with the oil or oil vapor as it is injected into the engine cylinder. For this purpose the pipe 66 is connected by a pipe 99 with the source of compressed air, and the pipe 99 is provided with a cut-off valve 100 and with a distributing valve 101, like or similar in construction and operation to the valve 72, as indicated by dotted lines in Fig. 1. 105

When the fuel valve 22 is to be operated by compressed air from such independent source, the valves 67 and 70 are closed, the 110 valve 100 is opened, and the rod 91 is connected with a lever 102, which will then be operated by the cam 93 to shift the distributing valve 101 at the proper times to admit compressed air to and release it from the cylinder extension 19. 115

When the fuel valve is operated by compressed air supplied either from the engine itself or from an independent source, a portion of such air, determined by the adjustment of the valve 33, may be admitted to the passage 25 and mixed with the oil supplied through the pipes 50 and 52, recess 27 and ports 28, before it is injected into 120 the engine cylinder. 125 130

When the valve 33 is opened, the check valve 32 prevents the escape of oil through the passage 25 into the cylinder extension 19.

Various changes in the details of construction and arrangement of parts of the fuel injecting and regulating mechanism may be made without departure from the principle and scope of the invention as defined in the following claims.

10 I claim:

1. In an internal combustion engine the combination with the cylinder, of a valve case provided with a nozzle inserted in an opening into the cylinder and having three coaxial valve seats of diminishing diameter towards the cylinder and divergent spray passages leading from the smallest seat into the cylinder, and a valve guided in said case and having three working faces fitted 15 to said seats and a longitudinal passage connected at its inner end by divergent passages with a clearance space between the valve and case and between the two outer seats and corresponding valve faces.

2. In an internal combustion engine the combination with the cylinder, of a valve case provided with a detachable nozzle inserted in an opening into the cylinder and having three coaxial beveled valve seats of 20 diminishing diameter towards the cylinder and divergent spray passages leading from the inner seat through the end of the nozzle into the cylinder, and a valve having a stem fitted and guided in the case and provided 25 with a detachable head having three beveled working faces fitted to said seats and a longitudinal passage connected by divergent passages with a clearance space between the valve and case and between the two outer 30 seats and corresponding valve faces.

3. In an internal combustion engine the combination with the cylinder, of a valve case provided with a nozzle inserted in an opening into the cylinder, a valve guided 45 and seated in said case, means for opening and closing the valve to inject fuel into the cylinder at the proper times, an oil reservoir, a two-stage pump comprising low and high pressure cylinders connected with each other 50 by a passage provided with a check valve opening towards the high pressure cylinder, a suction connection between the low pressure cylinder and the reservoir provided with a check valve opening towards the 55 pump, a discharge connection between the high pressure cylinder and valve case provided with a check valve closing towards the pump, a by-pass connecting the high pressure cylinder with the reservoir and provided with an adjustably weighted relief valve opening towards the reservoir, and oppositely working plungers fitted in the pump cylinders and having an actuating 60 connection with the engine.

4. In an internal combustion engine the

combination with the engine cylinder and piston, of a valve case provided with an enlarged cylinder extension and with a spray nozzle inserted in an opening into the cylinder, a fuel valve guided and seated in said case and having a longitudinal passage communicating with the nozzle and through lateral ports with the interior of the valve case and cylinder extension, an inwardly opening check valve in said passage between 70 said lateral ports, a regulating valve controlling the supply of air through said passage from the cylinder extension to the nozzle, a piston fitted in said cylinder extension and connected with the valve, a spring tending to close the fuel valve, a compressed air supply connection with the inner end of the cylinder extension, a valve in said connection operated by the engine to admit compressed air into the cylinder extension on 75 the compression strokes of the piston, and a pump operated by the engine and adapted to force oil into the valve case and through the passage in the fuel valve into the engine cylinder when said valve is opened.

5. In an internal combustion engine the combination with the engine cylinder and piston, of a valve case provided at its outer end with a cylinder extension and at its inner end with a nozzle inserted in an opening into the engine cylinder, an oil supply connection with the valve case, a compressed air connection between the inner end of the cylinder extension and the adjacent end of the engine cylinder, a fuel valve guided and seated in said case and having a passage leading from the oil supply connection into the nozzle, a piston fitted in the cylinder extension and connected with the fuel valve, a spring tending to close the fuel valve, a valve in the compressed air connection operated by the engine to admit compressed air from the engine cylinder into the cylinder extension and to open the fuel valve on the compression strokes of the engine piston, 100 and a pump in the oil supply-connection operated by the engine to force oil through the fuel valve and nozzle into the engine cylinder when the fuel valve is opened.

6. In an internal combustion engine the combination with the engine cylinder and piston, of a valve case provided at its outer end with a cylinder extension and at its inner end with a nozzle inserted in an opening into the engine cylinder, an oil supply connection with the valve case, a compressed air connection between the inner end of the cylinder extension and the adjacent end of the engine cylinder, a fuel valve guided and seated in said case and having lateral ports 115 in communication with the oil supply and compressed air connections and a passage leading from said ports into the nozzle, an inwardly opening check valve in said passage between the lateral ports, a regulating 120 valve

valve controlling the admission of air into said passage from the cylinder extension, a piston fitted in the cylinder extension and connected with the fuel valve, a spring tending to close the fuel valve, a valve in the compressed air connection operated by the engine to admit compressed air from the engine cylinder into the cylinder extension and to open the fuel valve on compression

strokes of the engine piston, and a pump in the oil supply connection operated by the engine to force oil through the fuel valve and nozzle into the engine cylinder when the fuel valve is opened.

In witness whereof I hereto affix my signature.

CHARLES F. BUSCHKE.
